UNITED STATES PATENT OFFICE.

HARRY H. EMMONS, OF ALLIANCE, OHIO.

SPRAY NOZZLE.

Application filed April 4, 1921. Serial No. 453,334.

To all whom it may concern:

Be it known that I, HARRY H. EMMONS, a citizen of the United States, residing at Alliance, in the county of Stark and State 5 of Ohio, have invented certain new and useful improvements in Spray Nozzles, of which the following is a specification.

This invention relates to new and useful improvements in nozzles for liquid 10 spray guns.

The primary object of my invention is to provide a nozzle for discharging liquid in the form of a spherical spray. The device is especially adapted or valuable for applying liquid carbon removers to the cylinder heads and combustion chambers of internal combustion engines, but may be used with equal facility in a number of other instances, as will hereinafter appear.

20 In the accompanying drawings, which are for illustrative purposes only and are therefore not drawn to scale:—

Fig. 1 is a side elevation, illustrating the application of my invention to a spray gun.

25 Fig. 2 is an enlarged side view of the nozzle and a portion of the nozzle pipe.

Fig. 3 is a front end view of the nozzle.

Fig. 4 is a view of the nozzle pipe and nozzle, with the outer end of the nozzle pipe 30 and the nozzle shown in section.

Fig. 5 is a vertical transverse section, taken on line 5—5 of Fig. 4, looking in the direction indicated by the arrows and Fig. 6 is a detail end view of the strainer.

35 Referring to the drawings for a more particular description of the invention and in which drawings like parts are designated by like reference characters throughout the several views, A represents a spray gun, 40 (shown in dotted lines) B the nozzle pipe and C my improved nozzle, as a whole.

The nozzle C, which is of general spherical form, is constructed in four separate parts 1, 2, 3 and 4, respectively. The four 45 parts or sections thus forming the nozzle, fit on the outer end of the nozzle pipe B, which is provided with one or more transverse ports or apertures 5 for the egress of the liquid. As shown, the meeting faces of 50 the nozzle sections are formed with small registering radial grooves for the discharge of the liquid, which is ejected in the form of a spherical spray.

The nozzle pipe B is provided near its 55 outer end with an exterior thread 7, on

which the inner section 1 of the nozzle screws and is slightly reduced from the outer end of said threaded portion to its outer end. The extreme outer end of said pipe is also exteriorly threaded, as at 8, for 60 screw threaded engagement with the outer nozzle section 4, which, when screwed into place, holds the four parts or sections forming the nozzle together as one unit.

A cylindrical strainer 9 of wire gauze 65 or other reticulated material surrounds the apertured parts of the nozzle pipe within the annular chamber 10 to collect any sediment that may be in the liquid and might otherwise stop or clog up the grooves 6.

The front end of the nozzle is provided 70 with a forwardly projecting mouth 11 formed with the outwardly flared side walls 12 and the small centrally and longitudinally disposed slit 13 for the discharge of 75 the liquid.

Among the many advantages that may be attained through the use of my invention, some of the more important may be briefly enumerated as follows:—

First: It may be used to throw a spherical needle spray where such is needed.

Second: It is especially valuable for applying liquid carbon removers in the heads and cylinders of internal combustion engines.

Third: It is valuable in cleaning or sterilizing milk bottles or in applying any liquids where a spherical spray is needed.

Fourth: It is especially valuable where 80 tiny outlets are needed in spherical spray nozzles to economize in the use of the liquid, as it permits of easy accessibility to clean.

Fifth: Permits the use of fine mesh strainers in small as well as large nozzles to 85 collect any sediment that might otherwise clog or stop up the discharge passages.

From the foregoing description taken in connection with the drawings, it is thought that the construction, operation and advantages of this invention will be readily understood without requiring a more extended explanation.

Having described my invention, what I claim as new and desire to secure by Letters Patent, is:—

1. A spherical nozzle comprising a plurality of separable sections formed in their meeting faces with small registering radial grooves, said nozzle adapted to discharge 110

liquid through said grooves in the form of a spherical spray.

2. In combination with a nozzle pipe, a spherical nozzle formed of a plurality of 5 separable sections formed in their meeting faces with small registering radial grooves, the inner and outer nozzle sections having screw threaded engagement with said pipe.

3. In combination with a nozzle pipe provided near its outer end with a plurality of 10 transverse discharge ports, a spherical nozzle

formed of a plurality of separable sections mounted on said pipe and when arranged in place forming an annular chamber surrounding said discharge ports, and a 15 strainer in said chamber around the apertured portion of said nozzle pipe, the inner and outer nozzle sections having screw threaded engagement with the nozzle pipe.

In testimony whereof I affix my signature.

HARRY H. EMMONS.
